UNITED STATES PATENT OFFICE.

G. W. FERGUSON AND H. H. FERGUSON, OF NEW YORK, N. Y.

MACHINE FOR ENAMELING ELLIPTICAL FRAMES, &c.

Specification forming part of Letters Patent No. 43,189, dated June 21, 1864.

To all whom it may concern:

Be it known that we, G. W. FERGUSON and H. H. FERGUSON, both of the city, county, and State of New York, have invented a new and Improved Ellipsograph; and we do hereby declare that the following is a full, clear, and exact description of the same, reference being had to the accompanying drawings, forming a part of this specification, in which—

Figure 1 represents a transverse vertical section of our invention. Fig. 2 is a plan or top view of the same.

Similar letters of reference in both views indicate corresponding parts.

This invention relates to a device which is particularly intended for the purpose of enameling picture-frames, but it is applicable equally well to other purposes.

The invention consists in the employment or use of an adjustable tool mounted on a rod, which is secured to two eccentric wrist-pins, which are adjustable in slotted cranks secured to the upper ends of arbors, to which a rotary motion is imparted in one and the same direction, and from the same shaft which imparts motion to the platform, carrying the picture-frame or other article on which an ellipse is to be described in such a manner that said tool in describing an ellipse retains a position corresponding with the radius of curvature at every point, and the various moldings produced by it will be of uniform width and shape throughout. The invention consists, also, in the application of hinged arms, in combination with the tool-holder and clamp confining the same to the bar, which is connected to the rotating platform carrying the picture-frame or other article to be acted on in such a manner that the tool is allowed to accommodate itself to any irregularities occurring in the surface of the picture-frame or other article to be acted upon, and arising either from irregularities in the position or in the manufacture of said frame or other article.

To enable those skilled in the art to make and use my invention, I will proceed to describe it.

A represents a frame made of wood or any other suitable material, and composed of a series of vertical bars or uprights, *a*, which also form the legs of said frame, and of a series of horizontal bars, *b b' b''*, which connect the uprights, as clearly shown in the drawings. The central

cross-bars, *b'*, support the journal-boxes, which form the bearings for the vertical arbor *C*, on which is mounted the platform or cross *B*, which carries the frame or other article to be acted upon by the tool.

A rotary motion is imparted to the arbor *C* by means of a bevel-gear, *c d*, from the horizontal driving-shaft *D*, which has its bearings in suitable boxes attached to two of the horizontal bars *b*, as clearly shown in Fig. 1 of the drawings. This shaft has mounted on its ends two bevel-wheels, *e e'*, which gear in pinions *f f'*, secured to the lower ends of the vertical arbors *E E'*. These arbors have their bearings in suitable boxes attached to the horizontal bar *b*, and the pinions *f f'* are so situated in relation to the bevel-wheels *e e'* that they cause the arbors *E E'* to rotate both in the same direction, and they are so proportioned that the said arbors will complete two revolutions for each revolution of the central arbor, *C*.

F F' are two cranks, which are mounted on the upper ends of the arbors *E E'*. These cranks are provided with slots *g g'*, which form the guides for the adjustable wrist-pins *h h'*. These wrist-pins carry the bar *G*, on which the tool *H* is mounted, and their position determines the eccentricity of the ellipse. It is obvious that the wrist-pins in both cranks must be set at precisely the same distance each from the center of its respective arbor in order to render the operation of the machine practicable. Spiral springs *i*, placed under the bar *G*, allow of depressing the same, so that the edge of the tool comes in contact with the surface of the work.

The tool *H* is secured to a tool-holder, *I*, by means of one or more screws, *i*, and this tool-holder is attached by means of arms *j* to the clamp or carriage *J*, which is adjusted in the desired position on the bar *G* by means of a set-screw, *k*. The arms *j j* are pivoted to the holder *I* and carriage *J* by screws *i'*, which adapt the holder *I* to vibrate horizontally, for the purpose to be presently explained.

The picture-frame or other article to be acted on by the tool *H* is adjusted in the proper position on the platform or cross *B*, and after the tool has been adjusted to the required eccentricity the machine is set in motion. The working-edge of the tool is shaped according to the moldings to be produced, and by its

action similar moldings are produced on the surface of the frame or other article secured to the platform or cross B. Any irregularities occurring in the moldings of the frame or in its position upon the platform or cross is compensated by the hinged arms j and by the peculiar action of the cranks F F'. The tool is always held in line with the radius of curvature, and consequently the moldings produced by it will be of uniform width and shape throughout. If the tool is not in line with the radius of curvature throughout the entire circumference of the frame or other article, the moldings produced appear narrow and cramped at those places where the position of the tool deviates from that of the radius of curvature.

It is obvious that this ellipsograph may be used in place of an ordinary trammel, and the shape of the tool may be altered to suit different kinds of work. The same effect, or nearly so, may be produced by using only one crank

and having the opposite end attached to a pin which moves in a slotted plate fixed permanently to the frame.

What we claim as new, and desire to secure by Letters Patent, is—

1. The combination of an adjustable tool, H, mounted on a rod, G, with the eccentric wrist-pins h h', which are adjustable in slotted cranks F F', rotating in the same direction, and with the rotating cross or platform B, all constructed and operating in the manner and for the purpose herein shown and described.

2. The hinged arms j, in combination with the tool-holder I, clamp J, bar G, and rotating cranks F F', constructed and operating substantially as and for the purpose set forth.

G. W. FERGUSON.
